REMOVABLE CYLINDER FOR LOCK

Abraham H. Golden, Stamford, Conn., assignor to The Yale & Towne Manufacturing Company, Stamford, Conn., a corporation of Connecticut

Application October 2, 1952, Serial No. 312,705

10 Claims. (Cl. 70—224)

This invention relates to the mounting of lock cylinders in the knobs of tubular locks, and particularly in locking knobs having a bulbous hand grasping portion and a sleeve portion. In locks of the particular class, the knob is assembled with its sleeve portion upon the outer end of a sleeve extending from the lock, termed a spindle sleeve, and is thereafter adapted to rotate the spindle sleeve and retract the usual latchbolt. The lock cylinder is positioned within the knob, and is equipped with a key plug that rotates relatively to the knob and spindle sleeve in retracting the latchbolt when the knob and spindle sleeve are locked against rotation.

It is customary to utilize in locks of this class a lock cylinder that is too large to pass through the sleeve of the knob, and the prior art resorts to various devices to enable the cylinder to be assembled and disassembled relatively to the knob. In one example of the prior art, the knob is formed of two parts, one part being removable, and this removable part covers a slot through which an extension of the cylinder moves as the cylinder is inserted through the knob sleeve. In this construction, the lock cylinder is actually mounted in the knob between the removable part and the front end of the knob. Thus, removal and replacement of the lock cylinder involves the removal of the inner end part of the knob as well as disassembly of the knob relatively to the spindle sleeve.

It has been proposed to insert the cylinder into the front or bulbous end of the knob, but to date no effective means have been developed for this type of assembly, notwithstanding its obvious advantages.

I have now conceived, in a lock of the class described, a novel construction whereby I am able to assemble and disassemble the lock cylinder relatively to the front end of the knob, as has long been desired. I do this through the simple utilization of the relationship of the knob, the spindle sleeve and the cylinder. Actually, as the first step in assembling my novel construction, I merely insert the lock cylinder through a relatively large opening in the front end of the knob. I thereby place the cylinder in assembled position relatively to the knob, but I do not actually mount the cylinder on the knob. I then assemble the knob, with the cylinder in it, to the spindle sleeve, and the knob then holds the cylinder relatively to the spindle sleeve while the spindle sleeve holds the lock cylinder relatively to the knob.

As a very important feature of my invention, I utilize between the knob and the lock cylinder an arrangement whereby the cylinder, in moving into the knob through the opening in its front end, undergoes a movement transverse to the knob axis. When the knob is assembled to the spindle sleeve, this sleeve then prevents transverse movement of the lock cylinder, and thereby holds the cylinder in assembled relation to the knob. The knob, in turn, prevents movement of the lock cylinder away from the spindle sleeve.

More in detail, I form upon the lock cylinder, in the preferred form of my invention, a laterally projecting detent part. This detent part prevents the cylinder from

2

moving axially through the opening in the front end of the knob, but does permit the cylinder to move through the opening when tilted away from the knob axis. By a movement of the lock cylinder from tilted position back to axial position when inserted in the knob, the detent part is juxtaposed to an inner surface of the knob. The knob is assembled to the spindle sleeve with the lock cylinder in this axial position, so that the cylinder enters the end of the spindle sleeve. The sleeve then prevents the cylinder from tilting and thereby holds the detent part juxtaposed to the inner surface of the knob to retain the cylinder in the knob. When the knob is removed from the spindle sleeve, the sleeve does of course release the lock cylinder so that it can be very easily tilted out of the knob. Through my novel arrangement, it is an extremely simple matter to install and remove the lock cylinder and yet this cylinder is securely retained when the knob is assembled on the spindle sleeve. Actually, no movable parts are used that are not otherwise required for the mounting of this knob itself on the spindle sleeve.

I prefer to form the front end of the lock cylinder with an enlarged head for covering the opening in the front of the knob. The detent part of the lock cylinder is formed preferably adjacent to the edge of this enlarged head, but somewhat spaced from it toward the inner end of the cylinder. The detent part is then juxtaposed to the inner surface of the knob adjacent to the opening while the head covers the opening. As a further feature, I provide between the cylinder and the knob a spring that prevents rattling of the cylinder relatively to the knob and the spindle sleeve. I prefer to place this spring in such a way between the detent part and the knob surface as to absorb shock applied to this surface by the detent part due to the slamming of the door in which the lock is mounted.

I have thus outlined rather broadly the more important features of my invention in order that the detailed description that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

Referring now to the drawing:

Fig. 1 is a longitudinal section showing the lock cylinder assembled to the knob and spindle sleeve in the preferred form of my construction; Fig. 2 illustrates the tilting movement of the cylinder as it is inserted into the knob, and Fig. 3 shows the cylinder, the sleeve, and the spring in exploded relation.

Referring now more particularly to the drawing, the lock cylinder in the preferred form of my novel construction is indicated by the numeral 10, and is shown in Fig. 1 assembled relatively to the knob 11 and a usual form of spindle sleeve 12. As is customary in locks of the particular class, the knob sleeve portion fits on spindle sleeve 12 to rotate integrally therewith and to be locked therewith by the usual means provided in the art. The lock cylinder has lateral extensions 14, 15, and these engage in slots in the sleeve 12 to prevent rotation of the cylinder relatively to the spindle sleeve, so that it may be said the spindle sleeve, the lock cylinder and the knob rotate as one unit when assembled, as shown in Fig. 1.

In my invention, I form in the bulbous or front end of

the knob 11 a relatively large opening 16 to permit the lock cylinder 10 with its extensions 14, 15 to be inserted into the knob. It is reiterated that it is not new merely to insert a lock cylinder through the front of a knob, but by my extremely novel construction I am able to insert and retain the cylinder in an effective manner.

It will be observed in Fig. 1 that I form a detent part 17 on the lock cylinder 10, and this detent part prevents movement of the cylinder through the opening 16 when the cylinder is in an axial aligned position relatively to the knob 11. However, by tilting movement of the cylinder 10, as shown in Fig. 2, the detent part 17 moves sufficiently toward the axis of the knob to permit the cylinder to pass through the opening 16.

In assembling the cylinder to the knob, it is merely necessary to insert the cylinder through the opening 16 while tilted away from the knob axis, and then to move the cylinder back into the knob axis. This places the detent part 17 in a position juxtaposed to the inner surface of the knob 11 near the edge of the opening 16, as shown in Fig. 1. I then assemble the knob 11 on the spindle sleeve 12, the body portion 13 of the cylinder simultaneously entering the spindle sleeve 12 so that the sleeve holds the cylinder in axial position. Because the cylinder 10 can no longer tilt away from the knob axis, the detent part 17 is held juxtaposed to the inner surface of the knob and retains the cylinder between this surface and a part of the spindle sleeve. Actually, the cylinder 10 in my invention is mounted in the spindle sleeve 12, and the knob 11 acts merely through the detent part 17 to hold the cylinder 10 in the sleeve. Those acquainted with the art will understand that the knob 11 is retained upon the spindle sleeve 12 by suitable means and, by way of example, I have shown for this purpose a dog 18 carried by the spindle sleeve 12 and fitting in a slot in the knob.

Upon the front end of the lock cylinder 10, I show an enlarged head 19 for covering the opening 16 in the knob 11. Preferably, the detent part 17 is formed integrally with the head 19 adjacent to its edge so as to be juxtaposed to the inner surface of the knob 11 when the head covers the opening. The detent part 17, as I have actually shown it, is formed on the lateral extension 14, this extension being integral with the head 19 and also with the body portion 13 of the cylinder.

In the preferred form of my invention, I interpose between the knob and cylinder a spring that absorbs shock between the detent part 17 and the knob 11 due to slamming of the door in which the lock is mounted. I have shown, for this purpose, a leaf spring 20 that is approximately C-shaped and that is slotted so as to be applied over the lateral cylinder extension 14. As shown in Fig. 1, the front end 21 of the spring 20 when assembled is positioned between the detent part 17 and the inner surface of the knob 11, while the opposed end 22 is engaged beneath a shoulder on the extension 14. Thereby the spring 20 because of its C-shape presses its central part against the spindle sleeve 12 and serves also to prevent rattling of the cylinder 10, knob 11, and sleeve 12 relatively to each other.

I believe that my extremely novel concept will now be understood, and that its advantages will be fully appreciated by those skilled in the art.

I now claim:

1. In a lock of the class described, a knob having an opening in its front end, a lock cylinder inserted through said opening into said knob, a part on said lock cylinder moving to a position juxtaposed to an inner surface of said knob through a tilting movement of said cylinder as said cylinder is inserted in said knob, said surface thereafter obstructing removal of the lock cylinder from the knob except by reverse tilting movement of the cylinder, a spindle sleeve, a part of said knob assembled on said spindle sleeve with the cylinder in said knob, and said spindle sleeve holding said lock cylinder against tilting

movement to prevent its release from said knob when said knob is assembled on said spindle sleeve.

2. In a lock of the class described, a spindle sleeve, a knob adapted to be assembled on said spindle sleeve and having an opening in its front end, a lock cylinder within said knob and having a head covering said opening, a part on said lock cylinder juxtaposed to an inner surface of said knob to prevent outward movement of said cylinder from said knob and thereby retaining said cylinder in said knob, said part moving into and out of retaining relation to said knob through a tilting movement of said cylinder relatively to said knob, and a portion of said spindle sleeve holding said lock cylinder against tilting relatively to said knob when said knob with said cylinder therein is assembled on said spindle sleeve.

3. In a lock of the class described, a spindle sleeve, a knob adapted to be assembled axially on said spindle sleeve and having an opening in its front end, a lock cylinder also adapted to be assembled axially on said sleeve, the front of said lock cylinder covering said opening while the remainder of the cylinder is within said knob, said cylinder being inserted into said knob by a tilting movement of said cylinder out of axial position, a detent part on said lock cylinder moving to a position juxtaposed to an inner surface of said knob as said cylinder moves back to said axial position within said knob, said inner surface of the knob thereafter obstructing removal of the lock cylinder from the knob except by reverse tilting of the cylinder, said knob and cylinder then moving axially into assembled position on said spindle sleeve to hold said lock cylinder assembled to said sleeve.

4. In a lock of the class described, a spindle sleeve, a knob adapted to be assembled axially on said spindle sleeve and having an opening in its front end, a lock cylinder adapted to be inserted through said opening into an axial position in said knob and entering said spindle sleeve when said knob is assembled on said sleeve, and a part on said lock cylinder admitted to said knob by a movement of said cylinder out of said axial position as it is inserted in said knob and moving to a position juxtaposed to an inner surface of said knob as said cylinder moves to said axial position whereby said knob when assembled on said spindle sleeve holds said lock cylinder assembled to said sleeve.

5. In a lock of the class described, a knob having a sleeve portion on one end and an opening in its opposed bulbous end, a lock cylinder inserted through said opening into a position aligned with said sleeve portion in said knob, a part on said lock cylinder moving to a position juxtaposed to an inner surface of said knob through a tilting movement of said cylinder as said cylinder is inserted in said knob, said surface thereafter obstructing removal of the lock cylinder from the knob except by reverse tilting movement of the cylinder, a spindle sleeve upon which said sleeve portion is assembled while said cylinder is aligned with said sleeve portion in said knob, and said spindle sleeve then holding said lock cylinder against tilting movement to prevent its release from said knob.

6. In a lock of the class described, a spindle sleeve, a knob adapted to be assembled axially on said spindle sleeve and having an opening in its front end, a lock cylinder in said knob, a detent part on said lock cylinder juxtaposed to an inner surface of said knob to retain said cylinder endwise between said knob and a portion of said spindle sleeve, said detent part moving into and out of retaining relation to said knob through a transverse movement of said cylinder relatively to the axis of said knob whereby to allow removal of said cylinder from said knob through said opening when said knob is removed from said spindle sleeve, and said spindle sleeve holding said lock cylinder against transverse movement relatively to the axis of said knob when said knob is assembled on said spindle sleeve.

7. In a lock of the class described, a rotatable spindle

sleeve, a lock cylinder assembled endwise to said spindle sleeve, coating surfaces preventing rotation and also transverse movement of said cylinder relatively to said spindle sleeve, a knob mounted on said spindle sleeve to rotate therewith, a detent part on said cylinder juxtaposed to a surface of said knob to hold said cylinder against endwise movement away from said sleeve, an opening in said knob allowing said detent part to move away from said surface of said knob through a transverse movement of said cylinder when said knob is disassembled relatively to said sleeve, and said coating surfaces by preventing transverse movement of said cylinder holding said cylinder assembled to said knob and spindle sleeve when said knob is assembled on said sleeve.

8. In a lock of the class described, a spindle sleeve, a knob assembled axially on said spindle sleeve and having an opening in its front end, a lock cylinder within said knob, a part on said lock cylinder juxtaposed to an inner surface of said knob adjacent to said opening to prevent outward movement of said cylinder through said opening and thereby retaining said cylinder in said knob, a spring acting between said cylinder and said knob to absorb shock against said inner surface due to slamming of the door in which the lock is mounted, said part moving out of retaining relation to said knob through a transverse movement of said cylinder relatively to the axis of said knob, and a portion of said spindle sleeve holding said lock cylinder against transverse movement relatively to the knob to the knob axis when said knob with said cylinder therein is assembled on said spindle sleeve.

9. In a lock of the class described, a spindle sleeve, a knob adapted to be assembled axially on said spindle sleeve and having an opening in its front end, a lock cylinder also adapted to be assembled axially on said

sleeve, said cylinder being inserted into said knob with a transverse movement of said cylinder relatively to the axis of said knob, a detent part moving to a position juxtaposed to an inner surface of said knob as said cylinder moves to axial position within said knob, said knob then moving axially into assembled position on said spindle sleeve to hold said lock cylinder assembled to said sleeve, and a spring acting between said cylinder, said knob, and said sleeve.

10. In a lock of the class described, a spindle sleeve, a knob having a sleeve portion adapted to be assembled axially on said spindle sleeve and also having an opening in its front bulbous end, a lock cylinder within said knob adapted to be inserted axially into said spindle sleeve, a head on said lock cylinder covering said opening while the remainder of the cylinder is within said knob, said cylinder being inserted into said knob through said opening with a tilting movement of said cylinder out of aligned position relatively to said sleeve portion of said knob, a detent part on said cylinder moving to a position juxtaposed to an inner surface of said knob as said cylinder moves back to a position aligned with said sleeve portion of said knob within said knob, said cylinder then moving axially into assembled position in said spindle sleeve as said knob is assembled to said sleeve to hold said lock cylinder assembled to said sleeve.
